his attorney

UNITED STATES PATENT OFFICE.

HENRY J. PLANT, OF ROCHESTER, NEW YORK, ASSIGNOR TO DEFIANCE CHECK WRITER CORPORATION, OF ROCHESTER, NEW YORK, A CORPORATION OF NEW YORK.

ROLLER.

1,284,443.

Specification of Letters Patent. Patented Nov. 12, 1918.

Original application filed February 15, 1917, Serial No. 148,781. Divided and this application filed February 9, 1918. Serial No. 216,306.

To all whom it may concern:

Be it known that I, HENRY J. PLANT, a citizen of the United States, and resident of Rochester, in the county of Monroe and 5 State of New York, have invented certain new and useful Improvements in Rollers, of which the following is a specification.

The present invention relates to rollers, and more particularly to the type in which 10 the surface of the roller is formed of yielding material as in inking rollers for printing machines, an object of this invention being to provide a simple and inexpensive means for securing the yielding material to 15 a spindle which forms the shaft of the roller.

To this and other ends, the invention consists of certain parts and combinations of parts, all of which will be hereinafter 20 described, the novel features being pointed out in the appended claims.

In the drawings:—

Figure 1 is an end view of a roller constructed in accordance with this invention; 25 Fig. 2 is a longitudinal section through the roller;

Fig. 3 is a perspective view of one of the retaining plates;

Fig. 4 is a perspective view of one of the 30 yielding disks of which the roller is made;

Fig. 5 shows an end view of one of the retaining plates, being secured to the spindle or shaft; and

Fig. 6 is a sectional view of one end of the 35 roller, showing one of the retaining plates being fitted in place.

In the illustrated embodiment of the invention the roller comprises a spindle or shaft 1 surrounded by yielding material, 40 preferably in the form of disks 2 of felt lying in abutting relation between two retaining plates 3. A feature of this invention is the securing of these retaining plates to the spindle. This is effected by providing each retaining plate 3 with a central opening 4, from which leads a slot 5 extending to one edge of the plate, the inner end of the slot being narrower than the diameter of the central opening 4. Near each end the 45 spindle or shaft 1 is provided with two an-

nular grooves 6 and 7, the diameter of the spindle at the groove 6 being substantially equal in width to the inner end of the slot 5, whereas the spindle at the groove 7 has a diameter substantially equal to the diameter 55 of the central opening 4.

By this arrangement it is possible to quickly attach the yielding material or working surface of the roller to the spindle. The yielding material is compressible in the 60 direction of the length of the roller, thus permitting each of the plates to be fitted or removed from the shaft. In fitting a retaining plate to the spindle the latter is shifted in its plane to cause the portion of the spindle 65 at the groove 6 to travel in the slot 5 until the central opening 4 is reached, when the material expands upon being released and forces the plate 3 laterally into the groove 7. Removal of the plate is effected by compressing the material 2 so that the plate may enter the groove 6, after which the plate 70 may be withdrawn from the spindle by way of the passage or slot 5. It will thus be seen that interlocking connections between the 75 plates and the spindle are provided, making the provision of separate fastening devices unnecessary. While the invention is stated as being used as an inking roller it is apparent that it may be used in other 80 rollers.

The present application is a division of an application filed by me on February 15, 1917, Serial No. 148,781.

What I claim as my invention and desire 85 to secure by Letters Patent is:—

1. A roller comprising a spindle provided with two pairs of proximate grooves, each pair having one of its members deeper than the other, the deeper groove being removed 90 farther from the adjacent end of the spindle than the other, two retaining members each having an opening whose diameter is substantially equal to the diameter of the spindle at the shallow groove, and also having a 95 slot leading from the opening to the edge of said retaining member, the inner end of the slot being narrower than the diameter of the opening so that the retaining member may be fitted over the spindle at the deeper 100

- groove and then be moved laterally of its plane to bring the opening over the portion of the spindle at the shallow groove, and yielding material surrounding the spindle 5 between the two retaining members.
2. A roller comprising a spindle, two retaining members having interlocking connection with the spindle, and yielding mate-

rial between said members holding the lat-
ter interlocked with the spindle.

3. An inking roller comprising a spindle, yielding material thereon, and a retaining plate for the yielding material held in interlocking connection with the spindle by the yielding material.

HENRY J. PLANT.
